for a period of time. The compositions are particularly useful in the control of weeds in legumes such as soybeans and alfalfa, and in the control of grasses such as ryegrass, fescue, and other grasses, particularly in the control of weeds in sugar beets.

of a U.S. patent application filed on June 12, 1964, now U.S. Pat. 3,457,063, which disclosed that various aminoxy compositions

3,520,674

CARBOXAMIDOXYACETATE ESTER HERBICIDES AND METHOD OF COMBATING WEEDS

Ralph P. Neighbors, Olathe, Kans., assignor to Gulf Research & Development Company, Pittsburgh, Pa., a corporation of Delaware
No Drawing. Continuation-in-part of applications Ser. No. 374,813, June 12, 1964, and Ser. No. 641,487, May 26, 1967. This application Sept. 15, 1967, Ser. No. 668,180. The portion of the term of the patent subsequent to June 10, 1986, has been disclaimed. Int. Cl. A01n 9/20; 9/22; C07c 83/08
U.S. Cl. 71—111 3 Claims

15 Abstract of the Disclosure

The method of the present invention comprises applying to the locus of the weeds a herbicidal quantity of a compound selected from the group represented by the structural formula

a compound selected from the group represented by the structural formula

in which X is one of the following;

and

and R is lower alkyl.

In a preferred embodiment of the method, weeds are combated in fields of grain crops such as oats, wheat and corn (maize) by applying to the locus of the weeds a herbicidal quantity of methyl or ethyl 2,4-dichlorophenoxyacetamidoxyacetate.

The practice of the invention is described in greater detail and specifically exemplified in the discussion which follows.

DETAILED DESCRIPTION OF THE INVENTION

(A) Synthesis of herbicides

The carboxamidoxyacetates are conveniently manufactured by reaction of the corresponding hydroxamic acid with a chloro- or bromoacetate, as exemplified by the following procedure for preparation of dodecyl benzamidoxyacetate:

To a solution of benzohydroxamic acid (13.7 g., 0.1 mole) in 200 ml. of 0.5 N NaOH was added a solution of dodecyl chloroacetate (26.3 g., 0.1 mole) in ethanol (1200 ml.). The mixture was refluxed 4 hrs., cooled and concentrated to one-half volume. The concentrate was diluted with water (500 ml.) and extracted with hexane (500 ml.). The hexane extract was concentrated under reduced pressure and the residual oil was dissolved again in hexane (500 ml.) and chilled to -20° C. to precipitate dodecyl benzamidoxyacetate (27.8 g.; 60%).

Calc'd for C₂₁H₃₃NO₄ (percent): C, 69.39; H, 9.15; N, 3.85. Found (percent): C, 69.55; H, 9.55; N, 3.72.

Benzohydroxamic acid is readily prepared by known procedures (Organic Synthesis, Coll. vol. II, p. 67). The chloroacetate ester may be prepared also by known methods, utilizing chloroacetic acid, which is an article of commerce. Other hydroxamic acids used for synthesis of

the carboxamidoxyacetates are also readily made by known procedures, with only such modifications as lie within the ordinary skill of the art.

The phthalimidooxyacetate esters are readily prepared from N-hydroxyphthalimide as illustrated by the following procedure, which was disclosed in U.S. Ser. No. 374,813:

A mixture of N-hydroxyphthalimide (0.1 mol, 16.3 g.), ethyl bromoacetate (0.1 mol, 16.7 g.) and dimethylformamide (200 ml.) was stirred at room temperature while triethylamine (0.1 mol, 10.1 g.) was added over a period of 30 minutes. After addition of the triethylamine the mixture was stirred at ambient temperature for an additional 5 hours. The reaction mixture was diluted with water (600 ml.) and the crude product was removed by filtration, washed with sodium bicarbonate solution, water, then with hexane and then was dried. There was obtained 18.2 g. of ethyl phthalimidooxyacetate (M.P. 95-97° C.; 73% yield).

Analysis.—Calc'd for C₁₂H₁₁NO₅ (percent): C, 57.83; H, 4.45; N, 5.62. Found (percent): C, 57.78; H, 4.44; N, 5.85.

All of the necessary intermediates for synthesis of the novel herbicides of this invention may be either purchased or made by published procedures. The general synthesis procedures exemplified above were employed to prepare the novel compounds which were evaluated as herbicides as discussed below:

(B) Use of carboxamidoxy- and carboximidooxyacetates

Specific compounds were employed as weed control agents on a variety of representative plant species under carefully controlled conditions so as to evaluate both activity and selectivity of herbicidal action, according to the following procedures:

(1) Post emergent activity: An aqueous dispersion of each active compound was prepared by combining 0.4 gram of the compound with about 4 ml. of a solvent-emulsifier mixture (3 parts of a commercial polyoxyethylated vegetable oil emulsifier, one part xylene, one part kerosene) and then adding water, with stirring, to a final volume of 40 ml.

The species of plants on which each compound was to be tested were planted in four-inch pots in a greenhouse. Ten to eighteen days after emergence of the plants, three pots were sprayed with an aqueous dispersion of the active compound prepared as described above, at a rate of 5 lb. of active compound per acre and at a spray volume of 60 gallons per acre. Approximately one week after the spray application the plants were observed and the results rated according to the following schedule:

Herbicidal effect

- 0=no effect
- 1=slight effect
- 2=moderate effect
- 3=severe effect
- 4=maximum effect
(All plants died.)

The same rating schedule was employed to judge pre-emergent results obtained according to the procedure below.

(2) Pre-emergent activity: A solution of each active compound was prepared by dissolving 290 mg. of the compounds to be tested in 200 ml. of acetone. Disposable paper half-flats were prepared and seeded with a variety of species of plant seeds, then sprayed with the acetone solution at the rate of 10 lb. of active chemical per acre of sprayed area. One flat, which had been seeded with alfalfa, brome, flax, oats, radishes and sugar beets was held at 75° F. day temperature; another seeded with corn, coxcomb, cotton, crabgrass, millet and soybeans was held at 85° F. Twenty-one days after seeding and treatment the flats were examined and herbicidal effect was rated according to the above schedule.

Both post-emergent and pre-emergent results are set forth in the following table.

I claim:

1. The method of combating undesired plant growth

The species of plants employed in the tests described above are selected so as to be representative of a great variety of families of related species and to give an indication of effects on common crops. The test data are indicative of the effects on individual, vigorous plants grown under beneficial conditions of temperature, moisture, fertility and illumination. In the field, weeds and crops are competing with each other, subject to varying weather and soil conditions. Usually no more than two or three species of weeds are a major problem in these competitive situations, so a herbicide which happens to be effective against only two species or even a single weed may be useful, providing substantial injury to the crop can be avoided.

Crop injury can be minimized by reducing the rate of application overall, or by application at the locus of the weeds between the rows at a higher rate than on the rows of crop plants. These techniques are well known. Since the objective of weed control is to alleviate the loss of crop yield resulting from competition with weeds, the decision is often made to accept minor crop injury in order to eliminate the weeds. For this reason, application rates may vary with the situation, according to prevailing farming practices. The tabulated data may be used as a guide in adjusting herbicide application rates in the practice of the method of this invention, taking into consideration the fact that herbicides are utilized somewhat less efficiently in the field than when used in carefully controlled experiments on a small scale.

which comprises applying to the locus of the plants a herbicidal quantity of a compound selected from the group represented by the structural formula

in which X is a member of the group consisting of

and

strongly herbicidal compounds to include at least

and R is lower alkyl.

2. The method of combating undesired plant growth which comprises applying to the locus of the plants a herbicidal quantity of a compound represented by the structural formula:

in which R is lower alkyl.

3. The method of combating weeds in legume crops 20 71-96, 106, 107, 108; 260-468, 471, 482, 326, 453

which comprises applying to the locus of the weeds a herbicidal quantity of ethyl benzamidoxyacetate.
